D. A. BROWN.

WATER CLOSET DISINFECTANT HOLDER.

APPLICATION FILED OCT. 1, 1914.

1,145,669.

Patented July 6, 1915.

UNITED STATES PATENT OFFICE.

DAVID A. BROWN, OF WOODBRIDGE, NEW JERSEY.

WATER-CLOSET DISINFECTANT-HOLDER.

1,145,669.

Specification of Letters Patent.

Patented July 6, 1915.

Application filed October 1, 1914. Serial No. 864,416.

To all whom it may concern:

Be it known that I, DAVID A. BROWN, a citizen of the United States, residing at Woodbridge, in the county of Middlesex and State of New Jersey, have invented certain new and useful Improvements in Water-Closet Disinfectant-Holders, of which the following is a specification.

This invention relates to water closet disinfectant holders, and belongs in the same class with devices intended to be arranged within the bowls of water closets, and constructed to hold soluble bodies of disinfecting substances or cleansing materials in the path of the flushing water.

This invention is believed to be an improvement on such devices now in common use or on sale, in the following particulars: In all the disinfectant holders for water closets with which the applicant in this case is acquainted, and in which balls of disinfecting and cleansing materials are employed, the balls are either held in one position by a wire container, or are arranged side by side upon a sheet metal supporter. The holders are all of metal. It has been found in practice that all metal containers or cages for the balls of whatever form such containers may be, soon corrode and cause the balls to adhere to them, even when the balls at the outset were freely movable. The balls being held against free movement, become themselves coated with filth, which communicates and spreads over and throughout the container. Thus, in place of operating to disinfect, deodorize and clean the bowl of the closet, the balls themselves, usually, a considerable time before they would be consumed in the regular service of the water closet, become a source of contamination.

It is the object of this invention to produce a disinfectant holder for water closets which is not made of metal alone, but, which may be composed either in whole or in part of celluloid or hard rubber. Those substances are found to be particularly durable for the peculiar situation and service required, and they do not corrode and accumulate filth to the same extent as do the exposed metals.

It is a further object of this invention to construct a holder of celluloid or of hard rubber for balls of disinfecting materials, the said holder having special formation and arrangement of its parts whereby it is

believed the balls are never held in any one position, but are floated up, thrown about, and rotated one against another by the water when the closet is flushed. The constant attrition between the balls and the holder operates to maintain all surfaces free from objectionable matter, and the solution of the balls is materially aided and their function as disinfecting agents correspondingly augmented.

Of the accompanying drawings setting forth the construction believed to be new in this invention, Figure 1, represents a side view of a water closet to which this invention has been applied, a portion of the side of the closet is broken away to disclose the position of this invention, a portion of which is also cut away. Fig. 2 is a plan view of a modified form of this invention showing the bar and the projecting teeth, before the teeth are curved. Fig. 3 is an end view of the modified form showing one manner of arranging the teeth to contain the disinfectant balls, and to prevent the balls from coming out of the end of the holder or container. Fig. 4 is a cross-section of the modified form of this invention, and shows the ends of the teeth cemented together forming an annular member projecting from the bar. Fig. 5 is a cross-section of the preferred form of this invention as illustrated in Fig. 1. The section is taken on the broken line $\alpha-\alpha$ of Fig. 6, which Fig. 6 is a front view of this invention, showing the means employed to close the ends of the series of annular projecting members. Fig. 7 is an edge view of the end portions and part of the middle portion of the auxiliary spring. Fig. 8 is a side view of one flat side of an auxiliary spring, and shows another method of rendering the end portions of the auxiliary spring less stiff than its middle portion, for the purpose hereinafter explained. Fig. 9 is a horizontal section of a water closet bowl just below the rim, showing this invention in place, and this figure is introduced to aid in the explanation as to why this invention is made stiffer in its middle portion than at its end portions.

Throughout the drawings and description the same letter is used to refer to the same part.

Considering the drawings, Fig. 1 shows a water closet bowl A, provided with the usual water channel B, having the discharge openings b directed into the bowl.

As best shown in Figs. 5 and 6, this invention comprises the longitudinal bar or body C of flexible and more or less elastic material. The bar is provided with the spaced teeth D, and the teeth are curved in the form of spaced rings or annular members projecting from the bar. The ends of the teeth are cemented or caused to adhere to the bar by heat. There is thus formed a series of spaced annular members projecting from the bar, and one end of the cage-like tube is in practice permanently closed by a cemented plate d, while the other end is stopped by the removable plug E. The balls e of disinfecting material are, therefore, held movably within the annular teeth.

The longitudinal member termed the backbone or bar C of this invention, is ordinarily the thickest portion, and there is embedded lengthwise in it the auxiliary spring F. The spring F is entirely inclosed in the backbone or bar C to prevent moisture from reaching the spring, a longitudinal cavity of any desired size being formed in the bar as a bed for the spring, and the opening for the insertion of the spring being finally cemented or otherwise closed watertight. It is important that the end portions of the spring F shall be less stiff than the middle portion, and methods of accomplishing such formation are shown in Figs. 7 and 8. The end portions of the spring may be made thinner or smaller or, the end portions may be pierced with stamped holes f to render the ends less stiff. This invention is not confined to any particular construction for that purpose.

The reason for making the auxiliary spring a part of this invention, is to give to the whole the necessary elasticity to keep it in proper position just beneath the rim of the water closet bowl as illustrated. Again, the reason for making the middle portion of the spring stiffer than the end portions, may be explained in connection with Fig. 9 of the drawings. In that figure it will be noted that the end portions of this invention fit the curving sides of the bowl closely. But, if the end portions of the combined bar and spring were just as stiff as the middle portions thereof, it has been found that the end portions will not bend sufficiently to properly conform to the shape of the bowl. The end portions would take up a position substantially along the broken lines in Fig. 9, and would not rest beneath the rim of the bowl as desired. When the end portions of this invention are rendered suitably less stiff than the middle, the ends curve closely along the inside of the bowl and are out of the way beneath the rim, as the middle portions are. The modified form of this invention set out in Figs. 2, 3, and 4, comprises a bar H with the teeth J and j on both sides. The bar has an auxiliary spring embedded in it

in the same manner and for the same purpose as explained for the preferred form of this invention. The spring is marked K. The teeth J and j may have their outer ends arranged a little distance apart, as shown in Fig. 3, or, those ends may be cemented together as shown in Fig. 4, making a series of annular members projecting from the bar H.

The operation of both forms of this invention is the same. The balls of disinfecting and cleansing material are placed in the tubular cage formed by the bar and teeth, and the whole is bent against the force of its own elasticity and that of the auxiliary spring, and placed immediately beneath the rim of the closet, as shown in Fig. 1. The flushing water from the openings b passes through between the teeth and turns the balls while dissolving them gradually. The flushing water in that way carries a quantity of disinfectant into the sewer, and, the odor of the disinfectant neutralizes any unpleasant smell in the vicinity of the closet at all times.

Having now described this invention, and explained the manner of its operation, what I claim is:—

1. A water closet disinfectant holder, comprising a bar composed of flexible and elastic material provided with curved spaced teeth, the surfaces of the said bar and of the said teeth being composed throughout of nonmetallic material, and the said bar being constructed thicker than the teeth to increase the stiffness of the bar.

2. A water closet disinfectant holder, comprising a bar composed of flexible and elastic material provided with curved spaced teeth, the surfaces of the said bar and of the said teeth being composed throughout of nonmetallic material, and an elastic metal strip embedded lengthwise in the said bar.

3. A water closet disinfectant holder, comprising a bar provided with teeth, the said teeth each having both ends connected with the said bar, and the said teeth being constructed to form annular members spaced apart and projecting from the said bar.

4. A water closet disinfectant holder, comprising a bar provided with teeth, the said teeth being constructed and arranged to form annular members spaced apart and projecting from the said bar in a series, and one end of the said series of annular members being closed, and the other end of the said series of annular members having a removable closure.

5. A water closet disinfectant holder, comprising resilient means for supporting disinfectant bodies in the path of the flushing water, the said supporting means being constructed stiffest in the middle portion and decreasing in stiffness toward the ends.

6. A water closet disinfectant holder, com-

prising resilient means for supporting disinfectant bodies in the path of the flushing water, the said supporting means having an auxiliary spring extending lengthwise thereof, the middle portion of the said spring being constructed stiffer than the end portions thereof.

7. A water closet disinfectant holder, comprising a bar provided with means for supporting disinfectant bodies, the said bar being bendable, and an auxiliary spring connected with the bar, the middle portion of the said spring being constructed stiffer than the end portions thereof.

15 8. A water closet disinfectant holder, comprising a bar provided with means for supporting disinfectant bodies, the said bar being bendable, and an auxiliary spring embedded lengthwise in the said bar, the middle portion of the said spring being stiffer than the end portions thereof.

9. A water closet disinfectant holder, comprising a series of substantially annular members spaced apart, the said members being connected together side by side forming a skeleton tube, means for closing the ends of the tube, and the surfaces of the said annular members and of the connecting portions being formed of celluloid.

30 10. A container for antiseptic bodies com-

prising a tube formed of a series of spaced apart and concentrically disposed celluloid rings, a celluloid backbone extending longitudinally of the tube and connecting said rings in order and celluloid end caps for closing said container.

11. A flexible and water-proof container for antiseptic bodies comprising a tube having the surface thereof formed of celluloid and a longitudinally extending metallic spring embedded in the wall of said tube and adapted to cause the container to return to its normal shape when distorting strains thereon have been removed.

12. A flexible container for antiseptic bodies comprising a tube formed of a series of concentrically disposed and longitudinally spaced apart rings, a flat backbone connecting said rings in order transversely thereof and forming a continuation of each ring circumferentially thereof, and a flat spring embedded in said backbone and having tapered ends adapted to lie flatly between supporting members.

In testimony whereof I affix my signature in presence of two witnesses.

DAVID A. BROWN.
